United States Patent Office

Des. 204,432

Patented Apr. 12, 1966

204,432

AIRCRAFT

Richard H. Prewitt, 658 Brooke Road, Wayne, Pa.

Filed June 1, 1965, Ser. No. 85,543

Term of patent 14 years

(Cl. D71—1)

FIG. 1 is a front perspective view of an aircraft, showing my new aircraft design in one mode of operation;

FIG. 2 is a front perspective view of said aircraft with the rotor blades extended with relation to the hub to which they are attached; and

FIG. 3 is a front perspective view of said aircraft showing the blade and hub members rotated through 90°.

I claim:

The ornamental design for an aircraft, substantially as shown and described.
